UNITED STATES PATENT OFFICE.

JOHN R. NUNNS, OF MILFORD, AND JOSEPH A. SMITH, OF NEW HAVEN,
ASSIGNORS TO THE AUTOMATIC SAFETY BOILER AND ENGINE COMPANY,
OF NEW HAVEN, CONNECTICUT.

AUTOMATIC BOILER-FEED.

SPECIFICATION forming part of Letters Patent No. 288,591, dated November 13, 1883.

Application filed March 16, 1883. (No model.)

To all whom it may concern:

Be it known that we, JOHN R. NUNNS, of Milford, county of New Haven, State of Connecticut, and JOSEPH A. SMITH, of New Haven, in the county of New Haven and State of Connecticut, have invented a new Improvement in Automatic Boiler-Feeds; and we do hereby declare the following, when taken in connection with accompanying drawings and the letters of reference marked thereon, to be a full, clear, and exact description of the same, and which said drawings constitute part of this specification, and represent, in—

Figure 1, a vertical central section, the parts in the condition of proper water-level in the boiler, or below it; Fig. 2, a vertical central section of the same, the parts in the position as when the water has risen too high.

This invention relates to an improvement in feeds for steam-boilers, having for its object to automatically maintain a constant water-level in the boiler; and it consists in a pump having a passage communicating from the water-level in the boiler to the active side of the piston of the pump, a valve in said passage which opens toward the piston, a passage leading from said pump to a valve-chamber which is provided with a valve one side of which is open toward the pump and the other exposed to boiler-pressure, a discharge from said valve-chamber, whereby the overflow received by said pump from the boiler and thrown into said valve-chamber will raise the said valve and open the discharge-passage from said chamber for the escape of the overflow, and a valve in the feed-water passage to the boiler in connection with said first valve, whereby when the said first valve is raised for the escape of the overflow it opens the water-way from the feed-chamber and turns the feed-water from its passage toward the boiler and permits it to escape, as more fully hereinafter described.

A represents the pipe which leads from the feed-pump to supply the feed-water to the boiler, and near the boiler is provided with the usual check-valve, to prevent the return flow of water, also in the usual manner. This feed-pump and check-valve are too well-

known to require detailed description in this specification.

From the boiler B, and at the point of desired water-level, an overflow-pipe, C, leads to a pump, D, a valve, *a*, being arranged between the boiler and the pump, which opens toward the piston, and so as to be closed as the piston descends. So soon, then, as the water in the boiler has risen to the water line or opening into the outlet C, the overflow will pass through this outlet-pipe to the pump D, and so that as the piston ascends it will draw into the cylinder any overflow which may pass from the boiler. Then as the piston descends it closes the valve *a*, and the water flows into a chamber, F, beneath the valve G. This valve G is in the form of a piston, and of a diameter corresponding to the cylinder in which it stands. From the valve-chamber is an outlet, H; but the length of the valve G is such that when in its down position it passes below the opening H, so as to cut off the passage from the chamber F through the outlet H, as shown. The valve-casing extends upward to form a chamber, I, above the valve, which is open to steam-pressure by a tube, L, which leads from the boiler above water-line into the said chamber I, so that the valve G stands under boiler-pressure at all times, and that that pressure may serve to hold the valve G in its down position, the upper surface of the valve G is made larger than the lower exposed surface, these differential surfaces giving a greater extent of bearing for the steam above the valve. As the water which has flowed from the boiler and been drawn into the pump D passes into the valve-chamber F, the pressure of the pump overcoming the pressure above the valve G raises that valve, as seen in Fig. 2, so as to permit the water to pass out through the opening H to the boiler or waste, as the case may be.

In order to cut off the inflow from the feed-pump when the water shall have risen above the water-line, a valve, *d*, is arranged in the feed-pipe A, opening into the pipe, with a chamber, M, below it, from which is a discharge-opening, N. From the valve *d* a stem, *e*, extends forward through a stuffing-box and

in substantially axial line with a corresponding stem, *f*, extending upward from the valve *G*, and also working through a suitable stuffing-box. When the valve *G* rises, as before described, it meets the stem *e* of the valve *d* and raises the valve *d* to open the passage into the chamber *M* below the valve *d*. Then the water which is delivered by the feed-pump will pass through into the chamber *M*, thence 10 through the waste-passage *N*, it flowing in this direction because there is no resistance to the flow in this direction, while the check-valve offers a great resistance in the passage to the boiler. Therefore when this valve *d* is so open 15 all the water delivered by the feed-pump will pass to waste, or wherever it may be desired.

In case the water in the boiler be at or below the water-level, steam only will pass to the pump and stand therein at boiler-pressure, 20 corresponding to the pressure above the valve. Then as the piston descends it will simply compress the steam; but the volume of steam is so small that the compression thus produced is not sufficient to raise the valve above the opening *H*—that is to say, the length of the valve *G* is made sufficient to yield to this compression of the steam without opening the discharge-passage *H*; but when the water comes 25 to the pump, that being not compressible, like steam, will raise the valve, as before described. In order that there may be this play or over-motion to the valve *G*, a short distance is left between the two valve-stems, so that the valve *G* may ascend a certain distance without acting upon the valve *d*. This may be done by 30 simply making the stems of such length that they will not come in contact until the valve *G* is raised above the point where the compression of the steam will naturally move it. 35 When the overflow or surplus water has been thus taken from the boiler, the differential pressure of the steam upon the valve *G*, as before described, will cause it to close. Then the valve *d* will also close, and the supply of 40 water again flow to the boiler.

It will be understood that the capacity of the feed-pump should be such as to supply substantially the ordinary consumption of the boiler, or very little more, and thus working a 45 constant level in the boiler will be maintained, because so soon as the level is reached the surplus water will flow to the regulating-pump *D* and be discharged; or, if the water falls slightly below that level, the feed will continue until that level is again reached.

As the stem *e* of the valve *d* will work with more or less friction through its stuffing-box, it is desirable to apply some device to positively close it at the proper time. To do this 60 we attach a stirrup, *h*, to the stem *f*, and through the upper end of that stirrup extend the valve-stem *e*, and within the stirrup fix a collar, *l*, on the stem *e*, with which the stirrup will engage as it descends and draw the 65 valve *d* down to its seat. Then, as the valve *G* ascends a shoulder, *m*, on the stirrup will strike the collar *l* and raise the valve *d*, as

seen in Fig. 2. To adjust the stirrup in proper relation to the two stems it is screw-threaded onto the stem *f*, and provided with a set-nut, *n*, as shown. The shoulder *m* may also be adjustable in the stirrup, so as to engage the collar *l* sooner or later.

The usual air-chamber for the feed-pump is provided, here represented at *P* as attached to 75 the shell or case in which the valve *d* is seated.

While we prefer to expose the valve *G* to boiler-pressure upon the end opposite that which receives the flow from the pump *D*, that pressure may be otherwise applied—as, 80 for illustration, by a spring adjustable to the standard boiler-pressure. We also prefer to arrange the valve *d* with its stem in axial line with the stem of the valve *G*, for the reason that it makes the connection between the two 85 simple and effective; yet they may be otherwise arranged, it only being essential that there shall be a connection between the two, so that when the valve *G* is raised it will impart its movement to said valve *d*.

We have illustrated the valve *d* as between the pump and the boiler, to turn the feed-water from its passage toward the boiler, and this we prefer; but it will be readily seen that it may be arranged on the opposite side of the 95 pump; so as to cut off the flow to the pump. We therefore wish to be understood by the term "open the water-way from the feed-pump to permit the escape of the water delivered by the feed-pump," to mean such an 100 arrangement of the valve *d* as will cut off the supply of water to the boiler.

We claim—

1. The combination of the pump *D*, having a passage communicating from the water-level 105 in the boiler to the active side of its piston, a valve in said passage opening toward the piston of the pump, a passage leading from said pump to a valve-chamber, a piston-valve, *G*, in said chamber, one end of said valve open 110 toward said pump, the other exposed to boiler-pressure, and a discharge from said valve-chamber whereby the overflow received by said pump from the boiler and thrown into said valve-chamber will raise said valve *G* 115 and open the escape-passage for said overflow, a valve, *d*, in the feed-water passage to the boiler, operating in connection with said valve *G*, whereby when said valve *G* is raised for the escape of the overflow it will also open 120 the water-way from the feed-pump to permit the escape of the water delivered by the feed-pump, substantially as described.

2. The combination of the pump *D*, having a passage communicating from the water-level 125 in the boiler to the active side of its piston, a valve in said passage opening toward the piston of the pump, a passage leading from said pump to a valve-chamber, a piston-valve, *G*, in said chamber, one end of said valve 130 open toward said pump, the other exposed to boiler-pressure, and of a greater area than said one end, and a discharge from said valve-chamber whereby the overflow received by

said pump from the boiler and thrown into said valve-chamber will raise said valve G and open the escape-passage for said overflow, a valve, *d*, in the feed-water passage to the 5 boiler, operating in connection with said valve G, whereby when said valve G is raised for the escape of the overflow it will also open the water-way from the feed-pump, to permit the escape of the water delivered by the feed- 10 pump, substantially as described.

3. The combination of the pump D, the 15 overflow-passage C from the boiler to the pump, valve *a* in said passage, valve-chamber F, connected with said pump by a passage, E, piston-valve G in said chamber, exposed to boiler-

pressure upon the end opposite that exposed 20 to said pump D, the valve *d* in the feed-water way, arranged in substantially axial line to the valve G, each of said valves G and *d* provided with valve-stems, and with a stirrup-connection, *h*, between said two stems, whereby 25 said valve G is free for a certain extent of movement before it communicates its motion to said valve *d*, substantially as described.
